TOY VEHICLE LAUNCHER

Raymond M. Toy, Los Angeles, Alan W. B. Nash, Torrance, and Brian S. Prodger, Los Angeles, Calif., assignors to Mattel, Inc., Hawthorne, Calif.

Filed Dec. 13, 1971, Ser. No. 207,725

Term of patent 14 years

Int. Cl. D21—01

U.S. Cl. D34—15 AJ

Fig. 5

Fig. 6

Fig. 7

FIG. 1 is a front perspective view of a toy vehicle launcher showing our new design, the front and rear portions of the track section being shown broken away to illustrate indeterminate length;

FIG. 2 is a right side elevational view thereof;

FIG. 3 is a front elevational view thereof;

FIG. 4 is a rear elevational view thereof;

FIG. 5 is a top plan view thereof;

FIG. 6 is a left side elevational view thereof;

FIG. 7 is a bottom plan view thereof;

FIG. 8 is a partial view of FIG. 2 on an enlarged scale, portions of the track having been omitted for ease of illustration; and

FIG. 9 is a bottom plan view of FIG. 8 with the track section omitted for ease of illustration.

We claim:

The ornamental design for a toy vehicle launcher, as shown and described.
